ROLLER SCREEN STRUCTURE OR THE LIKE

Zorn L. Bozin, Gary, Ind.

Application November 19, 1934, Serial No. 753,600

6 Claims. (Cl. 156—39)

This invention relates to roller structures and finds particular utility in the embodiment here described as a structure for a rolling or roller screen for windows or the like.

5 Among other objects, the invention aims to provide an improved rolling screen structure which can be economically produced in a few standard sizes at relatively low cost and which at the same time may be readily applied, by self-adjusting features disclosed by the invention, to slightly varying sizes of window frames or other openings. My improved screen can be readily installed without the aid of an expert mechanic since exact measurements need not be prede-
 10 termined and since the parts are easily and quickly assembled, at the same time providing a permanent installation where desired. For this purpose, the entire equipment may be sold as a unit, lending itself to packing in a relatively small space. The equipment is particularly
 15 adaptable to ordinary wood sash which is commonly found already in use in most homes and offices. It is just as readily adaptable, however, for a permanent initial installation in metallic window frames, for example, such as are used
 20 in railway vehicles.

My improved screen may be installed either inside or outside of the glass pane of the window, but I have here, for purposes of exemplification, shown it installed upon the inside of the glass pane. When thus installed, the screen may be raised partially, for purposes of opening the window, or may be entirely raised as in the winter time, and in all instances the screen is free from interference with curtains or other hangings and the window is readily accessible for cleaning.

Other objects and advantages will be apparent from the following description, taken together with the accompanying drawings, in which—

Figure 1 is a front elevational view of the inside of the window with my invention applied thereto;

Figure 2 is an enlarged vertical section of a portion of the structure of Fig. 1, taken on the line 2—2;

Figure 3 is a fragmentary cross-section taken on the line 3—3 of Fig. 2 and being also a section on the line 3—3 of Fig. 1, enlarged;

50 Figure 4 is a fragmentary vertical section taken on the line 4—4 of Fig. 1, still further enlarged;

Figure 5 is a partial front elevation of the structure of Fig. 1, being one side of the structure with the screen web removed;

55 Figure 6 is a view similar to Fig. 5 of the other

side of the structure but with the screen web in place;

Figure 7 is a sectional view taken on the line 7—7 of Fig. 5;

Figure 8 is a partial side elevational view taken on the line 8—8 of Fig. 6;

Figure 9 is an end view of the spring roller, other parts associated therewith being shown in section;

Figure 10 is a longitudinal axial view of the 10 roller taken on the line 10—10 of Fig. 9;

Figure 11 is a partial sectional view taken on the line 11—11 of Fig. 9 showing the details of the crank arm; and

Figure 12 is a view showing further details of 15 the structure of Fig. 11, being a section on the line 12—12 thereof, with parts in alternative position.

Referring in detail to the illustrative construction shown in the drawings, I have shown 20 a conventional window frame 10 which is here suggested to be of wood and comprises the usual vertical side frame members 11 and 12, upper frame member 13, and sill 14. These frame members are bordered inwardly by the usual vertical stiles or moldings 15, 16 and the upper molding 17 against which moldings the lower sash 18 of the window may slidably abut, the upper sash 19 being offset outwardly of the lower sash, all of which is ordinary window construction. 30

Secured to the molding 15 as by screws 20 I have shown an end portion 21 of the housing indicated generally by the numeral 22, the end portion 21 being disk-like and the housing generally being of a hollow somewhat semi-cylindrical conformation extending transversely across the window frame between the moldings 15, 16.

The housing end 21 has a semi-circular portion 23 extending axially thereof about one side of 40 its perimeter and facing, in this instance, toward the window panes 18, 19 and this semi-circular portion 23 telescopes with a similar semi-circular portion 24 of the housing 22, these parts being rotatively located together by turned-over 45 edges 25, 26 on the housing portion 24 between which, as in a groove, are received the free edges of the portion 23 permitting sliding adjustment of the portions 23, 24 to accommodate various widths of the windows. At the opposite side of 50

the window the housing portion 24 is continued, in this instance integrally, to form an end portion 27 secured to the molding 16 generally similar to the separable end portion 21. Each of the housing end portions 21 and 27 is continued 55

downwardly in an integral depending portion 28, and the portion 28 is of channel form as by having integral side walls 29, 30 which at their point of proximity with the disk-like part 21 merge respectively into the semi-circular axially extending part 23 of the housing and into another shorter semi-circular axially extending part 31 of the end portion 21, thus placing the channels 28 in communication with the interior of the housing. As shown in Fig. 2, the curve axially extending parts 23 and 31 are spaced apart as at 32 and 33 to permit the part 24 of the housing to slide therein for purposes of extensibility or contractability of the housing as already pointed out.

At the lower end of the channeled portions 28, the side walls 29, 30 of the channels converge leaving a restricted vertical slot 34 therebetween, for a purpose presently pointed out. Also, at their lower ends, the channeled continuations 28 of the housing end portions are telescoped within similarly channeled guideways 35 extending from the channel portions 28 down to the window sill 14. The guides 35 each have a vertically extending base 36 and side walls 37, 38 spaced apart to provide the guideway 39 which communicates with the channels 28 and through them with the housing 22. The guide walls 37, 38 also desirably converge leaving a restricted vertical slot 40 therebetween providing a continuation of the slot 34. The guides 35 may be secured to the moldings 15, 16 as by screws 41 passing through holes 41a in the flanged portions 42 of the guides. By this telescoping action of the guides and the depending channel portions 28 of the housing, adjustment may be made for varying heights of windows. As best shows in Fig. 3 the guides 35 may be formed of a single piece of metal transversely bent upon itself.

In order to quickly determine the correct rotative position of the housing end portions 43, to cause the depending channels 28 to be alined with the guides 35, these channels may have a lateral projection 44 the outer end of which may be readily alined with the edge 45 of the molding 15 or 16 as the case may be.

The housing end portions 21 and 27 provide bearings to support shafts or pins 46 and 47 of a spring roller 48, next described, and which extends within the housing 22 transversely of the window-frame. Spring roller 48 includes a cylindrical rod 49 in this instance of wood, which at its right-hand end has the support pin 47 secured concentrically therein, a collar 50 limiting insertion of the pin 47 and leaving an outwardly projecting journal part 51 which is received to turn freely in a conventional bearing (not shown) carried centrally by and within the housing end portion 27. At its other end, the rod 49 is axially and centrally recessed for a considerable portion of its length as at 52. The recess 52 is desirably lined by a metal tube 53 which is secured from rotation with respect to the rod by a nail 54. The nail 54 also secures against rotation with respect to the rod a plug 55 received within the tube 53 at the inner end of the recess 52. The plug 55 at its outwardly directed end has a diametrically reduced annular extension 56, the hollow interior of which is lined by a metallic thimble 57. A spindle 58 also conveniently of wood is received in the recess 52 and has an inner reduced end 59 which is rotatively received in the thimble 57. The spindle 58 has a metallic sleeve 60 at its outer end and extending for a portion

of the length of the spindle rotatively secured to the spindle as by a nail 61. Anchored at one end as at 62 to the sleeve 60 and at its other end as at 63 to the plug 55 is a helical torsion spring 64 within the coils of which the spindle 58 enters, the spring thus surrounding the spindle and the annular extension 56 of the plug 55, these parts thus maintaining the spring in position. It will be noted that the supporting pin 46 is carried by the spring roller 48 through the intermediation of the spindle 58, and the supporting pin 46 terminates outwardly in a flattened key or feather portion 65 (Fig. 11) which is received in a narrow slot 66 in a bracket 67 secured centrally of and within the housing end portion 21. Thus the supporting pin 46 and bracket 67 are keyed together against rotation, it being understood that the slot 66 is open at one end so that the feather 65 may be slid thereinto in one rotative position after the journal 51 at the other end of the roller is received in its bearing. It will be further understood that support pin 46 is secured in the spindle 58 against rotation so that as the rod 49 is rotated on its journal 51 and on the bearing provided by the spindle portion 59, the spindle 58 will be held from rotation and will thus wind up spring 64. In accordance with my invention, also fixed on and rigid with the support pin 46 and the spindle 58 is a crank arm 68 by which the spring 64 may be readily wound up, before the feather 65 is received in its bearing 67, thereafter the crank arm functioning as later pointed out.

The spindle 58 is supported at its outer end by an inwardly turned annular flange 69 formed integrally with a cap 70 telescoped over the end of the rod 49. A similar cap 71 is slipped over the other end of the rod 49, these caps having annular lips 72 received in annular peripheral grooves in rod 49 so that the caps may be rotated with respect to the rod but are held from disengagement therewith. Each of the caps 70 and 71 also has an integral outwardly extending annular flange 73, formed in this instance by bending the material of the caps upon themselves. Thus the rod 49, together with the flanges 73, provide in the nature of a reel upon which is reeled in this instance a flexible web of copper screening 74. To secure one end of the screen web to the rod 49 of the roller 38, I desirably provide a longitudinally extending groove 75 in the periphery in the roller 49 in which the free end of the web may be entered. A narrow elongated keeper 76 is then inserted over the end of the web as best shown in Fig. 2. The web and keeper are inserted in the groove 75 when the caps 70 and 71 are turned so that the slots 77 therein register with the groove 75. When the web and keeper are inserted in the groove 75 the caps 71 are then turned, for example as shown in Fig. 5, to place the slot 77 in the groove 75 out of register thus locking the end of the screen web with its keeper 76 in the groove and to the rod 49.

The free end of the screen web 74 has secured thereto and extending transversely of the web and window frame a bar 78, here shown as comprising two narrow elongated plates 79, 80 which clamp between them as by screws 81, the free end of the web 82, as best shown in Figs. 3, 4 and 6. It will now be understood that the screen web 74 secured to the spring roller 48 may be inserted as a unit in the housing 22, having the bearings therein as already described, and the free end of the web margined by the bar 78 then led

through the channels 28 and the guide-ways 39 so as to be drawn downwardly of the window frame. To permit ready insertion of the roller and screen, I desirably cut away the walls 30 of 5 the channels 28 as at 82a, as best shown in Figs. 2, 5 and 6.

As will be readily understood, when the roller with the screen thereon is so mounted and the web led downwardly to unreel it off the roller, 10 to cover the window, the spring 64 will be wound up to create the tendency to automatically re-reel the screen upon the roller by the unwinding torsional action of the spring. To selectively resist this re-reeling action and to maintain the 15 screen web covering the entire window or covering it partially as may be desired, I provide vertically spaced-apart shoulders such as the rack teeth 83 conveniently formed integrally with the inner face of the wall 37 of the guideways 35, these 20 teeth thus providing racks extending vertically of the window frame at each side thereof. To engage with these racks I provide a shoulder 84 at each end of the plate 79 forming one part of the transverse bar 78. The shoulder 84 is flat 25 facing upwardly so that it will vertically abut any one of the teeth 83 as may be desired to prevent re-reeling of the screen on the spring roller. To 30 yieldingly maintain the shoulders 83, 84 in engagement, I provide a coil spring 85 having a pair of extended legs 86, 87 one of which, the leg 86, bearing against the plate 80 and the other 87 against a detent 88 pivoted as at 89 within an 35 enlargement 90 of the bar member 80, as best shown in Fig. 4, the detent in turn pressing against the wall 38 of the guideway. When it is desired 40 to cause the screen to be re-reeled and to move the web upwardly, the bar 78 is moved toward the guide wall 38 and away from the guide wall 37 against the force of the spring 85. Facing downwardly, I provide that the shoulder 84 is inclined 45 as at 91 providing a cam surface so that when the screen is drawn downwardly the bar 78 is cammed automatically away from the shoulders or teeth 83, as it passes each tooth, thus facilitating downward movement of the web and eliminating the necessity for the user to consciously move the bar 78 away from the wall 37. The 50 corner 92 of the detent 88 is desirably rounded to minimize friction between it and the wall 38. Also the detent has a tail 93 which is pressed by 55 the spring 85 against the wall 94 of the bar extension 90 when the bar is removed from the guideways 39, thus limiting rotation of the detent 88 on its pivot 89.

Throughout its intermediate portion between the guideways 35, the bar 78 clamps between its plate members 79, 80 a pad or buffer 95 desirably of felt or the like which abuts the window sill 14 when the screen is drawn down thereto. At its 60 ends, however, the pad 95 may be omitted and the plate 79 offset as at 96 (Fig. 3) toward the plate 80 where the bar enters the slot 49 in the guideways.

For convenience in lowering and raising the 65 screen 74 as described, the bar 78 may be provided with the usual handle 97.

Inasmuch as in accordance with my invention, 70 unwinding of the screen 64 and consequent re-reeling of the screen is resisted by engagement of the bar 78 with the guideway racks, as described, it is desirable, when the spring roller and screen thereon are removed from its bearings in the housing 22, that means be provided on the roller itself to prevent unwinding of the spring. 75 Such means I have shown in association with the

crank arm 68 which as already explained may be used for winding the spring. As best shown in Figs. 11 and 12 the crank arm 68 carries a small plunger 98 movable inwardly and outwardly of the crank by means of a stem 99 having a small handle 100 at its outer end, the stem sliding in a bearing 101 on the crank. When it is desired to remove the roller and screen from the housing, the plunger 98 is pushed inwardly from the position shown in Fig. 11 to the position shown in Fig. 12, whereupon, upon a tendency of the spring 64 to unwind, thereby rotating the crank 68, the crank, upon partial rotation will, by means of the plunger 98, engage the stop 102 formed as a projection upon the face of the cap 10 of the rod 49, the stop 102 being then in the path of the plunger 98 and the surface 103 of the stop abutting the plunger. It will be understood, as best shown in Fig. 9, that the tendency of the spring 64 to unwind rotates the rod 49 relatively to the 20 crank 68 in the direction of the arrow 104. When the spring roller is in its housing 22 the crank arm 68 passes through a slot 105 in the axially extending wall 31 of the end housing member 21, and engagement of the crank with the wall 31 25 as at 106 locates the position of the crank so that it is always accessible to the user on the proximate side of the roller. Should the plunger 98 be in the path of the stop 102 when the roller and screen are in the housing for operation and it is desired to pull the screen downwardly, thereby winding the spring 64, provision is made for automatically retracting the plunger 98 out of the path of the stop 102. As here shown, face 107 of the stop 102 is beveled so that upon rotation 30 of the stop in a direction opposite to the arrow 104, the face 107 of the stop will cam the plunger 98 out of its path, whereupon the screen may be drawn downwardly and thereupon the engagement of the bar 78 with the rack of the guideways prevents unwinding of the spring 64 until it is desired to again remove the screen and roller from the housing, whereupon the plunger 98 is pushed inward manually to again prevent this 35 unwinding.

As best shown in Fig. 8 the base 36 of the guideways 35 is cut away as at 108 to facilitate telescoping of the channels 28 therewith.

As best shown in Fig. 8, the screen 74 together with the housing 22 provides a complete through foraminated closure for the window-frame, the housing 22 contacting the upper molding 17 of the window-frame and the screen flexing itself about the interior of the housing and slidably contacting the turned-over edge 26 thereof as the 50 screen moves up and down, thus completely closing any openings for insects or the like.

Claims to the housing structure for the roller screen here disclosed are made in my co-pending divisional application Serial Number 162,095, filed 60 Sept. 2, 1937.

Obviously the invention is not limited to details of construction shown for purposes of exemplification. Furthermore, it is not essential that all features of the invention be used conjointly, as 65 various combinations and sub-combinations may be advantageously employed.

Having described my invention, I claim:

1. In a structure of the class described, the combination including a spring roller comprising 70 a reel member having, an axial recess therein, a torsion helical spring in said recess, a spindle in said recess telescoped within the spring, one end of the spring being anchored to the reel and the other end to the spindle, a crank arm keyed to the 75

spindle outside the roller, and means associated with the roller and crank arm permitting relative rotation of the roller with respect to the spindle in one direction to wind the spring but restraining rotation in the opposite direction to unwind the spring.

2. The structure of claim 1 wherein the reel includes a cylindrical rod grooved longitudinally and a flanged cap telescoping upon the rod at each end thereof, at least one of said caps being rotatable with respect to the rod and having a slot therein of substantially the same width as the groove adapted to register with the groove in one rotative position of the cap with respect to the rod and to be placed out of register with the groove in another position to at least partially close the groove.

3. In a structure of the class described, the combination including a spring roller comprising a reel member, an axial recess therein, a torsion helical spring in said recess, a spindle in said recess telescoped within the spring, one end of the spring being anchored to the reel and the other end to the spindle, a crank arm keyed to the spindle outside the roller, mechanism associated with the roller and crank arm permitting relative rotation of the roller with respect to the spindle in one direction to wind the spring but restraining rotation in the opposite direction to unwind the spring, said mechanism being manually adjustable to permit rotation of the roller with respect

to the spindle in both directions, and means carried by one of the members for automatically placing said mechanism in said last-mentioned adjusted position.

4. The structure of claim 1 wherein the crank arm carries a movable plunger reciprocable longitudinally of the crank arm and wherein the reel carries a stop fixed thereon for direct abutment with the plunger in one longitudinal position of the plunger with respect to the crank arm upon relative rotation of the spindle and reel in one direction.

5. The structure of claim 1 wherein the crank arm carries a movable plunger reciprocable longitudinally of the crank arm and wherein the reel carries a stop fixed thereon for direct abutment with the plunger in one longitudinal position of the plunger with respect to the crank arm in relative rotation of the spindle and reel in one direction, and wherein the stop has a cam face engageable with the plunger in relative rotation of the spindle and reel in the opposite direction, said cam face engaging the plunger to move it out of the path of the stop.

6. The structure of claim 1 wherein means are provided associated with the crank arm for preventing engagement with said means associated with the roller when the roller is in position within the housing.

ZORN L. BOZIN. 30
